UNITED STATES PATENT OFFICE.

GUSTAV GROSSMANN, OF BERLIN, GERMANY.

DIATHERMIC APPARATUS.

Application filed October 7, 1927, Serial No. 224,589, and in Germany November 23, 1926.

This invention relates to improvements in apparatus employed for diathermic treatments, and has particular reference to electrode heating means therefor.

5 It is desirable to heat the electrodes that are to be used for diathermic treatments before they are laid upon the body of the patient.

In accordance with the present invention 10 this heating is effected by means of ballast resistances or ballast lamps that are built into the diathermic apparatus and which are employed, as is well known, for the protection of the oscillatory circuits, and particularly 15 of the spark gap, from injurious heating in case of only a slight employment of the energy or a total non-use thereof. For this purpose the resistances are built-in in the vicinity of one part of the wall of the apparatus. For the purpose of receiving the 20 electrodes a niche, tunnel or a pipe, on the walls of which the ballast resistances are arranged, may be provided in the casing, or, more simply, a certain portion of the cover 25 of the casing which is suitable for the placing of the electrodes thereon may be used for heating the latter.

One form of the invention is represented 30 in the drawing, wherein the figure is a perspective view of the apparatus.

All parts of the diathermic apparatus, with the exception of the measuring device and the connection terminals, are housed in the box-like casing *k*. The cover of this casing 35 is provided with perforations *d* at two

places, that is, on opposite sides of the measuring device *m*. Directly below these perforations, the ballast resistances *w* are built in, as is shown on the one side where the cover is partly broken away for purposes of illustration. These ballast resistances may consist of insulating plates which are wound with a ribbon or wire of resistance metal.

The treatment electrodes to be heated are laid upon the perforated portions of the 45 cover. The air that is heated by the ballast resistances then rises through the perforations from the interior of the casing and heats the electrodes.

50 What is claimed is:

1. In a diathermic apparatus, a casing, and ballast resistances in said casing for the protection of the oscillatory circuit of the apparatus arranged in the vicinity of one 55 wall of said casing in such manner that the electrodes of the apparatus which are placed in said vicinity are heated by said resistances.

2. Apparatus in accordance with claim 1, characterized by said wall being provided 60 with perforations through which the heat passes to said electrodes.

3. Apparatus in accordance with claim 1, characterized by said wall being provided 65 with perforations through which the heat passes to said electrodes and said resistances being built in the casing directly beneath the cover thereof.

GUSTAV GROSSMANN.
